MONOCHROMATOR

Orrin Weston Pineo, Milo, Maine, assignor, by
mesne assignments, to American Cyanamid
Company, New York, N. Y., a corporation of
Maine

Original application September 2, 1938, Serial No.
228,127. Divided and this application Septem-
ber 26, 1940, Serial No. 358,570

5 Claims. (Cl. 88—14)

This invention relates to monochromators and more particularly, to monochromators for use in spectrophotometers. This application is a division of my copending application, Serial No. 5 228,127 filed September 2, 1938 now Pat. No. 2,227,510 issued January 7, 1941, which application in turn is a continuation in part of my earlier application, Serial No. 54,829 filed December 17, 1935, which application in turn was 10 a division of my earlier application, Serial No. 11,600 filed March 18, 1935 issued as U. S. Pat. No. 2,126,410 on August 9, 1938.

In the past, difficulties have been encountered with monochromators to be used through a 15 wide band of the spectrum, particularly in conjunction with spectrophotometers, due to the fact that the band of light defined by the slits in the monochromator, and particularly by the exit slit, varies in wave length or frequency 20 range in different parts of the spectrum if the slit width is maintained constant. As a result, a broader band of wave length or frequency is transmitted at one part of the spectrum than at another which is undesirable for spectrophotometric use. It has been proposed to provide a drive, for example by cams, which varies the slit width at different parts of the spectrum to maintain a constant range of wave length or 25 frequency in the band of light transmitted by the slit. Such a device represents an improvement and permits maintaining a constant range of wave length or frequency in the transmitted band. However, this range cannot be changed except by dismantling a portion of the device 30 and inserting cams of different shape.

Monochromators according to the present invention are provided with means for maintaining bands of constant wave length or frequency throughout the spectrum and for varying the 40 width of the band by adjustable mechanism so that bands of any desired range of frequency or wave length can be chosen and the range thus chosen maintained throughout the spectrum.

Essentially, the present invention is directed 45 to a drive linkage between a portion of the monochromator which selects successive bands of light through the spectrum for transmission and movable slit defining members, the linkage 50 consisting of variable ratio drive members, such as cams, which maintain a given range of band throughout the spectrum and adjustable linear drive mechanisms, the variable ratio drive members being so constructed that the movement of 55 the linear drive portion is in proportion to the

logarithm of the slit width so that a displacement of the adjustable linear drive will vary the width of the slit by an amount depending on the amount of displacement. The drive linkage may consist of two or more portions, for 5 example, the variable ratio drive portion may be divided into two sets of cams with an adjustable linear drive connection between them.

The monochromator may have one or more slits controlled by the present invention. In 10 some cases, it is sufficient to control only the exit slit. However, where a double monochromator is used with a recording spectrophotometer, more accurate results are obtained by providing all three slits with 15 drives according to the present invention. The The invention will be described in detail in conjunction with the drawings which show a general type of monochromator slit drive in conjunction with a double monochromator suitable 20 for use with a photoelectric spectrophotometer.

Fig. 1 is a diagrammatic plan view of a monochromator;

Fig. 2 is a side view, partly broken away, of a slit adjusting mechanism and one connecting 25 slit;

Fig. 3 is a vertical section along the line 3—3 of Fig. 2;

Fig. 4 is an enlarged detail section along the line 4—4 of Fig. 3;

Fig. 5 is a plan view of the top of the adjusting mechanism of Fig. 2 on an enlarged scale;

Fig. 6 is an elevation of the cam drive for slit width adjustment.

In the monochromator shown diagrammatically in Fig. 1, the table 28 carrying the record chart of the recording spectrophotometer and moving on balls 29 (Fig. 2) is moved by a motor or other suitable drive producing a slow movement as is conventional with recording spectrophotometers. The positions of the various lines in the spectrum produced by a prism monochromator are non-linearly related to the wavelengths due to the fact that dispersion is not uniform through the spectrum. The variation in dispersion requires the interposition of a drive of varying ratio between a table moving linearly with wavelength and the movable portion of the monochromator which shifts the wavelength selector slit through the spectrum. This drive of varying ratio is shown as a cam 30 (Fig. 3) which is driven by the table 28 and in turn moves a bell crank 31 through the roller 33. The bell crank is pivoted at 32 and on its other arm carries an adjusting screw 34 and flex-

ible portion 35 which connects it to the rod 36. This rod in turn moves a carriage 44 on which is mounted the mirror 45 with the knife edge 46 defining the wavelength selector slit.

5 The operation of the monochromator is as follows: light from the light source 47 passes through condensing lenses 48, entrance slit 49 and a second lens 50 to the prism 51. The spectrum formed by this prism passes through lenses 10 52 and 53, strikes the mirror 45 in which it is reflected, passes through the lens 54, the second prism 55 and lens 56 to the exit slit 57. Movement of the carriage 44 moves the slit, defined by the knife edge 46 and its image in the mirror 15 45, through the spectrum produced by the first prism and therefore determines the location in the spectrum of the band which passes out through the exit slit 57 after a further removal of unwanted wavelengths by the second prism 20 55. The cam 30 transforms a uniform motion of the table 28 into a non-uniform motion of the carriage 44 so that a given displacement of the table 28 gives always the same change of wavelength of the band of light leaving the monochromator. Therefore, the surface of the table or a record paper carried by it can be uniformly 25 graduated in terms of wavelength of the band leaving the monochromator. If it is desired to have a record bearing a scale uniform in frequency of light rather than wavelength, the shape of the cam 30 will have to be changed accordingly.

Since the width of slit corresponding to a band of given wavelength range will vary in different 30 parts of the spectrum, the present invention provides for changing the width of the three slits of the monochromator; i. e., 49, 57 and the selector slit between knife edge 46 and its mirror image so that their change in width will exactly 35 compensate for the change in width of a band of constant wave length (or frequency) range. This is effected by interposing a drive of varying ratio between the bell crank 31 and the members defining the slits. This is shown in 40 Figs. 1 and 2 as a cam gear composed of the cams 39 and 40 (detailed in Fig. 6) and a cam 37 carried by the bell crank 31 (Fig. 3). The cam 37 drives a roller 38 which is mounted in the sector arm 27 journaled on the shaft 21, the sector arm being pulled to the left of Fig. 3 by the tension of a spring (not shown). This arm is provided with a slot in its upper end through which passes a clamp screw 25 mounted in a framework 26 and provided with a collar. A second sector arm 22, beside the arm 27, is fastened to the shaft 21 by the pin 23. This arm is provided with an enlarged threaded portion opposite the slot in arm 27 which threaded portion takes the threaded end of the clamp screw 25 50 (Fig. 4). Both sector arms move in a framework 24 which serves as a guide and limits their motion. By the clamp screw 25, the two arms 22 and 27 can be clamped together in any desired relative positions, in which case the motion imparted to arm 27 by the cam 37 is transmitted to the arm 22 and by it to the shaft 21.

The shaft 21 rotates the two cams 39 in the case of slits 49 and 57. They, in turn, drive the cams 40 which are keyed to the shafts 41. These latter shafts are provided with two threaded portions 42 and 43 having right and left hand threads respectively engaging with the slit defining members 58 and 59 respectively. Rotation of the shafts 41 serves to move the slit defining 70 members together or apart depending on the

direction. The profiles of the cams 37, 39 and 40 are so chosen that the movement of the slit defining members is such as to keep constant the wavelength range (or frequency range) of the beam of monochromated light leaving the exit 5 slit 57. The selector slit defined by the knife edge 46 and its image in the mirror 45 is actuated in a similar manner which is shown on Fig. 1. Shaft 21 carries equal beveled gears 60 which turn the shaft 61 at the same rate as the shaft 10 21. The end of shaft 61 is provided with an enlarged portion having an internal slot in which slides a spline on shaft 62. This shaft 62 rotates the cam 63 which in turn rotates the cam 64 keyed to the shaft 65 whose threaded end moves 15 the knife edge 46. Cams 63 and 64 are similar respectively to cams 39 and 40. The thread on shaft 65 has a pitch substantially equal to that of the threaded portions 42 of shafts 41 increased by the factor cosecant of the angle of light incidence and reflection at the mirror 45. As the carriage 44 moves, the splined shaft 62 slides in the end of shaft 61 and is maintained at all times in positive driving relation thereto.

It will be apparent that there is interposed 25 between the drive of the carriage 44 and the slit defining members a linkage consisting of two variable ratio drives (cam 37 and cams 39 and 40 or alternatively, cam 37 and cams 63 and 64) between which there is an adjustable linear drive 30 embodied in the adjustable clamping of the sectors 27 and 22. When it is desired to change the relative wave length range of the band of monochromated light, this can be effected by 35 adjustment of the linear drive portion of the linkage. At any adjustment, the first varying ratio portion of the drive will take care of maintaining the wave length range of the band constant throughout the spectrum. Adjustment of the linear portion of the linkage is simply effected by screwing out the clamp 25 so that arms 40 27 and 22 are no longer connected together. These arms may then be moved relative to each other within the limits defined by the slot in 45 27 and clamped in their new relative positions. This results in a selection of a different wave length range of the band for the monochromator and the same wave length range is then automatically maintained through the spectrum by the first portion of the linkage, cam 37, which is 50 a varying ratio drive. For convenience scales are mounted on the top surfaces of the two sector arms 22 and 27. This is shown in Fig. 5 where one of the arms carries a scale marked for purposes of example in milli-microns and the other 55 carries an index cooperating therewith.

In the linkage shown in the drawings, the cams 39 and 40 and 63 and 64 are exponential cams so that a given displacement in the adjustable linear drive portion will result in varying 60 the slit width by an amount depending on the amount of angular displacement of the shafts 21 and 61 with respect to sector arm 27 resulting from the adjustment. The cams are preferably designed according to the well-known principle of circular gears to insure rolling contact.

While I have described my invention in detail with reference to its embodiment in a particular type of monochromator and further with that monochromator used for the particular purposes of a recording spectrophotometer, nevertheless after understanding my invention, it will be obvious to those skilled in the art that changes and modifications may be made, without departing from the spirit or scope of the invention, 70 75

whereby the invention may be applied to other types of monochromators and to monochromators used for other purposes and whereby further the invention may be employed in a single monochromator to produce more than one variation of its slits; for instance, a single monochromator might transmit, as selected, either intervals of wavelength, intervals of frequency, or amounts of energy from an associated light source, which intervals or amounts are maintained constant at a selected value throughout the range of wavelength setting of the monochromator.

What I claim is:

1. In a double monochromator having in optical alignment a light source, a variable width entrance slit, a spectrum forming prism, an intermediate slit consisting of a mirror and slit defining member both mounted on a movable carriage, a second prism and a variable width exit slit and driving means for moving the carriage so as to cause the exit slit progressively to receive bands of light through the spectrum, the improvement which comprises means actuated by a part of said driving means to vary the width of the slits so that they transmit in all portions of the spectrum light bands of constant range of a function of wavelength, said means containing a linkage inter-connecting the drive means and the slit defining members, the linkage including a cam actuated by said drive means and having a profile proportional to the logarithm of the slit width for constant range, the cam driving an adjustable linear portion of the linkage which in turn drives an exponential cam drive to the slit defining members, the exponential cam drive having a ratio variation such that the motion in the linear portion of the linkage is proportional to the logarithm of the movement of the slit defining members, and means for adjusting the adjustable linear portion of the linkage to effect a relative movement of one cam with respect to the other.
2. A monochromator according to claim 1 in which the exit slit defining members are knife edges mounted in frames threaded onto a threaded shaft with right and left hand threads respectively, and the said shaft is driven by the exponential cam drive.
3. In a monochromator having a light source, means for forming a prismatic spectrum from the source having spectral bands of equal wavelength range which vary in width in different portions of the spectrum, members movable relative to each other defining a variable width exit slit, means for selecting for transmission through the slit light from a desired portion of the spectrum and driving means for actuating said selecting means, the improvement which comprises a drive linkage interconnecting said driving means and slit defining members, said linkage consisting of a cam driven by the drive means and having a profile which gives a drive proportional to the logarithm of the slit width for transmitting a light band of constant range, a sector arm journaled on a shaft and moved by said cam, a second sector arm keyed to said shaft and provided with means for locking it to the journaled sector arm, an exponential cam drive driven by the said shaft and driv-

ing the movable slit defining members, the ratio of said cam drive being such that the angular rotation of the shaft is proportional to the logarithm of the movement of the slit defining members, whereby the displacement of the sector arms relative to each other will increase or reduce the width of the slit by an amount corresponding to the extent of such relative displacement.

4. In a monochromator having a light source, means for forming a prismatic spectrum from the source having spectral bands of equal wavelength range which vary in width in different portions of the spectrum, members movable relative to each other defining a variable width exit slit, means for selecting for transmission through the slit light from a desired portion of the spectrum and driving means for actuating said selecting means, the improvement which comprises a drive linkage interconnecting said driving means and slit defining members, the linkage having three portions, the first being a variable ratio drive actuated by the driving means and having a ratio variation corresponding to the variation in physical width of the slit for constant band range throughout the spectrum, a second adjustable linear drive portion driven by the first portion and a third portion interconnecting the linear drive portion and the slit defining members including a variable ratio drive which transforms linear movement into exponential movement so that the movement of the linear portion of the linkage is proportional to the logarithm of the movement of the slit defining members, and adjusting means in the adjustable linear portion of the linkage for causing movement of the second variable ratio drive with respect to the first and means for locking the adjustment in any adjusted position.

5. In a monochromator having a light source, means for forming a prismatic spectrum from the source having spectral bands of equal wavelength range which vary in width in different portions of the spectrum, members movable relative to each other defining a variable width exit slit, means for selecting for transmission through the slit light from a desired portion of the spectrum and driving means for actuating said selecting means, the improvement which comprises a drive linkage interconnecting said driving means and slit defining members, the linkage having three portions, the first portion being a cam actuated by the driving means and having a profile proportional to the logarithm of the slit width for constant band range throughout the spectrum, the second portion being a linear portion driven by the cam which in turn drives a third portion comprising an exponential cam actuating the slit defining members, the exponential cam drive having a ratio variation such that the motion in the linear portion of the linkage is proportional to the logarithm of the movement of the slit defining members, and adjusting means in the linear portion of the linkage for causing movement of the exponential cam with respect to the first cam and means for locking the adjustment in any adjusted position.
